UNITED STATES PATENT OFFICE.

LEWIS R. DAVIS, OF SAN FRANCISCO, CALIFORNIA.

MOLD.

Application filed January 10, 1927. Serial No. 160,260.

This invention relates to a mold and more particularly to a mold wherein may be cast a double walled piston shown, described and claimed in my co-pending application 5 #148,483, filed November 15, 1926.

An object of my invention is the provision of a mold which is novel, easily assembled and dis-assembled and from which the cast piston may be readily removed.

10 With the foregoing object in view, together with such other objects and advantages as may subsequently appear, this invention resides in the construction and arrangement of parts hereinafter described and claimed, 15 and illustrated in the accompanying drawings, in which—

Figure 1 is a plan view of the mold;

Figure 2 is a section taken on 2—2 of Figure 1;

20 Figure 3 is a section taken on line 3—3 of Figure 1;

Figure 4 is a section taken on line 4—4 of Figure 2;

25 Figures 5 and 6 are respectively elevations and side views of part of one member of the mold;

Figures 7, 8 and 9 are respectively front elevation, side elevation, and back elevation of another member of the mold; and

30 Figures 10 and 11 respectively are front and side elevations of another member of the mold.

Referring to the drawings for a more detailed description thereof the mold of my invention comprises a plate 10 shown in Figure 1, as being square, and having there-through apertures 12. Encircling the apertures 12 on the upper face of the plate 10 are annular flanges 13. A sectional core as shown in Figures 2 and 3 depends from the plate 10. The core comprises a central section 15, which, as shown in Figures 2 and 3 is screwed into aperture 16 in the plate 10. The section 15 is also shown in Figures 10 and 11. Figure 10 shows that central section 15 is provided with an aperture 17, through which passes a pin 18 shown in Figures 1, 3, and 4.

The central section 15 is also provided with 50 vent hole 19 near its upper end and is provided at its lower end with a groove 20. The sides of the central section 15 are provided with projections 22 shown in Figures 10 and 11. The sides of the central section 55 15 are contacted by members 25 which are alike and which are illustrated in Figures 7,

8 and 9. The upper parts of the outer faces of the sections 25 are tapered as shown in Figure 8, and are provided with flat faces 25^a, which are at slight angles to each other; 60 the outer faces of the members 25 in the lower parts thereof are arcuate, as shown in Figure 4. The inner sides of the sections 25 are provided with grooves 28 in which are disposed projections 29, which are flushed 65 with the inner faces of the members. The members 25 are provided with vent holes 30. The construction of the outer circles of central section 15 and the inner circles of sections 25 are such that the projections 22 70 and 29 in contacting with each other, prevent the sections 25 from sliding out from the other parts of the mold. The core also comprises members 32, which are alike and which contact with the wider sides of the central 75 section 15. The construction of the members 32 is shown in Figures 5 and 6.

The members 32 are arcuate on the lower portions of their outer surfaces, as indicated by their numeral 33 in Figures 5 and 80 6. The upper portions of the outer faces as indicated by the numeral 34 is tapered, and is provided with flat faces 35, which are at small angles to each other. The lower portions 33 of the outer faces are provided 85 with grooves 37, extending from the bottom of the section 32 to a recess 38, which encircles and is concentric with an aperture 39. The tapered pin 18 passes through the aperture 39 of both sections 32. 90

The upper portions of the core sections 32 are provided with vent holes 39^a and 39^b. The hollow cylindrical shell 40 encircles the core of the mold and depends from the lower part of the plate 10, to which it is threadedly 95 secured as shown in Figure 2. The shell 40 in its upper portion has its interior surface tapered to fit the outer surfaces of the outer sections of the core. The lower portion of the shell 40 is provided with a series of spaced 100 parallel slots 41 lengthwise thereof.

It will be seen from Figure 2 that the shell 40 is a hollow cylindrical member 45, having therein a hole 46 into which the molten metal may be poured for filling the mold. 105

It will be noted that the cylindrical member 45 comprises parts 45^a and 45^b which are each provided with registering apertures 47 through which fastening means may be inserted in order to hold the two parts together. 110

The bottoms of the parts 45^a and 45^b are laid over with semi-circular plates 50 and

51 respectively. These plates are provided with semi-circular flanges 50^a and 50^b, and threadedly receive bolts 52 and 53 respectively. When the parts 45^a and 45^b are separated 5 after the mold has been filled and the metal cooled, the bolts 52 and 53 may be pushed inwardly and the plates 50 and 51 loosened from the cast metal.

The pin 18 may be held in place by a wedge 10 54 as shown in Figures 3 and 4. The plate 10 is provided with the holes 55 interiorly of the bosses 13.

While I have described one embodiment of my invention, modification thereof may be 15 readily devised without departing from the spirit of my invention, and it is to be understood that such modifications come within the scope of the appended claims.

I claim:

20 1. A mold comprising a plate, a sectional core extending downwardly therebelow, a cylindrical shell surrounding said core and spaced therefrom through part of its length and a sectional cylindrical member surrounding said shell and spaced therefrom for part of its length.

2. A mold comprising a plate, a sectional core extending downwardly therebelow, a cylindrical shell surrounding said core and spaced therefrom through part of its length and a sectional cylindrical member surrounding said shell and spaced therefrom for part of its length, said plate extending over the cylindrical member and having apertures 35 through which the cylindrical member may be reached.

3. A mold comprising a plate, a sectional core extending downwardly therebelow, a cylindrical shell surrounding said core and spaced therefrom through part of its length, and a sectional cylindrical member, surrounding said shell and spaced therefrom for part of its length, said core being grooved longitudinally in its upper end for venting purposes.

4. A mold comprising a plate, a sectional core extending downwardly therebelow, a cylindrical shell surrounding said core and

spaced therefrom through part of its length, and a sectional cylindrical member, surrounding said shell and spaced therefrom for part of its length, a pin passing transversely through said core, said shell and said sectional cylindrical member and means associated with the pin for holding the sections 55 of the cylindrical member.

5. A mold comprising a plate, a sectional core extending downwardly therebelow, a cylindrical shell surrounding said core and spaced therefrom through part of its length, and a sectional cylindrical member surrounding said shell and spaced therefrom for part of its length, said core comprising a central section screwed into said plate.

6. A mold comprising a plate, a sectional core extending downwardly therebelow, a cylindrical shell surrounding said core and spaced therefrom through part of its length, and a sectional cylindrical member surrounding said shell and spaced therefrom for part 70 of its length, said core extending below said shell.

7. A mold comprising a plate, a sectional core extending downwardly therebelow, a cylindrical shell surrounding said core and spaced therefrom through part of its length and a sectional cylindrical member surrounding said shell and spaced therefrom for part of its length, and there being a space between the free end of the core and said sectional 80 cylindrical member.

8. A mold comprising a plate, a sectional core extending downwardly therebelow, a cylindrical shell surrounding said core and spaced therefrom through part of its length 85 and a sectional cylindrical member surrounding said shell and spaced therefrom for part of its length, and means for holding together the sections of said core.

9. In a mold of the character described, a 90 plate having a core suspended therefrom, a cylindrical member surrounding the core and a shell interposed between the core and the said member, and spaced from both of them.

LEWIS R. DAVIS.
